UNITED STATES PATENT OFFICE

MARTIN JOHANNES JØRGENSEN, OF FREDERIKSBERG BY COPENHAGEN,
DENMARK

EXCHANGEABLE HEEL FOR BOOTS AND SHOES

Application filed May 24, 1930, Serial No. 455,175, and in Czechoslovakia August 30, 1927.

The present invention relates to a heel for boots and shoes of which the lower part or pad can be exchanged. By means of the present invention there is obtained both a 5 readily detachable connection between the pad and the remainder of the heel and a low cost of production of the separate parts.

The previously known detachable heels are inconvenient in use by reason of the numerous mechanical connecting parts and more expensive to produce so that they have not been used to any considerable extent in practice. The heel produced according to the present invention, however, can be applied and detached readily, while the parts thereof are cheap to produce.

The detachable heel part or pad is previously provided with a suitable number of projecting sleeves which are secured to the pad in a particular manner and when applying the pad are forced into corresponding sleeves which are fitted and secured in the material of the heel when the latter is being manufactured. Into the centre of the heel is fitted 25 a screwed sleeve in which is adapted to move a screw of which the head bears against the pad. When the latter is to be removed the screw is moved slightly outwardly by means of a suitable tool so that its head presses the pad outwardly to such an extent away from the remainder of the heel that the pad can be easily removed by hand and replaced by another pad.

One form of construction of the invention 35 is illustrated in the accompanying drawings wherein:

Fig. 1 shows a vertical section of the detachable pad on the line B—B of Fig. 2,

Fig. 2 is a cross section on the line A—A 40 of Fig. 1,

Fig. 3 shows an underside view of a pad in position,

Figs. 4—8 show altered forms of execution 45 of the fastening of the sleeves or taps in the pad,

Fig. 4 showing a form to be used for leather pads in section on the line E—E of Fig. 5,

Fig. 5 the pad seen from the underside, 50 Figs. 6 and 7 showing in a similar way one

form for pads of caoutchouc, Fig. 6 being a section on the line G—G of Fig. 7,

Fig. 8 shows in section another form for caoutchouc pads.

In Fig. 1, 1 indicates the heel itself of 55 leather or wood, 2 the leather pad applied thereto. The latter when being manufactured or in every case before use is provided with three or more projecting sleeves 3, extending towards the heel, each of which, at its end adjacent the pad 2, is provided with a flange 3^a. These sleeves are preferably secured to the pad by passing tapered pins or pegs 4 through suitable holes in the pad and forcing them into the sleeves 3 so that they 60 are firmly connected to the sleeves and the pad material thus forming a secure connection between the pad 2 and the sleeve 3. In this form the pad is ready for application and is placed on the market in this form.

For the reception of the sleeves 3 the heel 1 is provided with a corresponding number 65 of bushes 5 of which the internal diameter is a close fit on the outer diameter of the sleeves 3 so that the clamping action or friction between these two members is sufficient to retain the pad on the heel. To apply the 70 pad it is therefore sufficient to force the sleeves 3 into the bushes 5.

In order to secure the bushes 5 in the wood 75 or leather heel 1 their forward cylindrical end, before driving them into the heel, may partly have fitted therein tapered plugs 6 of metal.

When driving in the bush the tapered plug 80 is forced completely or almost completely into the bush thus enlarging the front end thereof, as shown in Fig. 1 so that it is impossible for the bush to become disengaged from the heel.

In order to facilitate the removal of the 85 detachable heel part or pad from the remainder of the heel the following arrangement is provided according to the invention:

At the centre of the heel there is secured an internally screwed bush 7 in which a screw 90 8 is adapted to move.

The head 9 of this screw, in the example 95 illustrated, projects beyond the surface of the heel and bears against the inner surface of the pad 2. The screw is provided with a cen-

tral hole 10 while opposite thereto the pad 2 is provided with a hole, gradually reduced towards the outside of the pad and normally closed by a plug 11 of rubber, inserted from the inside, so as to prevent the entrance of moisture. By means of a pointed object, for example a prong formed on a key or spanner adapted to be fitted into the hole 10, the plug 11 can be removed easily and the key can be fitted into the hole 10 of the screw 8. When unscrewing the screw 8 its head 9 forces the pad 2 away from the heel so that the pad can be easily removed by hand and replaced by another pad.

15 The pad 2 may be provided with a celluloid disc 12 on its side turned towards the heel to prevent the entrance of moisture.

In the example shown the disc surrounds both the sleeves 3 and the head 9 of the screw. 20 The head 9 may however fit into a recess in the material of the heel 1 in which case the disc 12 only serves to surround the sleeves 3 and a central hole serving for the passage of the key.

25 The flanges 3^a may also be provided with teeth, grooves or the like on the side turned towards the pad so as to engage more firmly with the material of the pad.

In the case of wide heels a larger number 30 of connecting members 3 and 5 is used, for example five to eight.

According to Figs. 4 and 5 screwthreaded taps 3 are inserted into the fixed heel portion by means of corresponding holes arranged 35 in the leather pad 2. the said taps are provided with conical flanges at the upper ends of their screwthreaded portions to serve as supporting means for the pad.

According to Figs. 6 and 7 the taps 3 have 40 inside the caoutchouc pad 2 a conical circular flange 14, and in their lower end a head 15. For these taps holes 16 are formed from outside in the caoutchouc pad, these being provided with an exterior enlarged part for 45 taking up the head 15, and an inner, narrow part for taking up the neck of the tap lying between the flange 14 and the head 15. These taps are from outside pressed through the holes in the caoutchouc, the conical flange 50 14 extending through the narrow part of the hole, which thereupon is drawn tight together about the neck of the tap, so that the tap gets an exceedingly solid position, being at one end supported by the flange 14 and at the other end by the head 15. After the fastening of the pad the outward part of the holes 16 are filled out with a caoutchouc plug corresponding to the plug 11 in the central 55 hole of the pad.

According to Fig. 8 the taps 3, being provided with a relatively broad head 17, are molded into the caoutchouc pad by the making of this. Each of these taps is made in one piece by pressing or the like, 60 so that the tap stalk itself cannot be detached

by the use of it from the head, and the pad thus be lost.

The disc of celluloid 12 is suitably made use of by the form of execution shown in Figs. 4 and 5, while it is not thought to be used by the pads of caoutchouc. The forms of execution shown in Figs. 4-8 make possible a still cheaper making of the metal parts than the one shown in Figs. 1-3. Besides it will be understood that all the parts of the device may be easily produced mechanically at a low cost.

The arrangement can also be used easily in that when applying the detachable part it is only necessary to press it firmly against the heel and for the purpose of removal the screw 8 is turned a few times thus releasing the pad and enabling it to be readily removed by hand.

It is also of advantage in connection with the invention not to effect the connection of the parts by springs as these are weakened in use thus rendering the heel part or pad liable to be lost.

Having now particularly described and ascertained the nature of my said invention and in what manner the same is to be performed, I declare that what I claim is:—

1. A heel for boots and shoes with a detachable wearing part or pad adapted to be brought into engagement with the rigid heel part by pressure, characterized in that in the rigid heel part are provided smooth bushes 5 for the reception of projecting sleeves 3, previously secured to the detachable heel part or pad 2, and an internally screwed centrally disposed bush 7 for the reception of a screw 8 adapted to be actuated from the outer side of the heel part or pad 2 when in position and when unscrewed serves to separate the part 2 from the rigid part 1.

2. A heel for boots and shoes according to claim 1, characterized in that the bushes 5 are secured in the heel 1 by means of tapered metal plugs 6 which are first partly fitted into the forward ends of the bushes and when driving the bushes into the heel are forced into the bushes and expand these.

Signed at Copenhagen, in the Kingdom of Denmark, this 30th day of April A. D. 1930.

MARTIN JOHANNES JØRGENSEN.
